Primary Examiner — Ricky Pham(74) *Attorney, Agent, or Firm* — McCormick, Paulding & Huber LLP(57) **CLAIM**

The ornamental design for a bottle warming device, as shown and described.

DESCRIPTION

FIG. 1 is a front elevational view of a bottle warming device showing a new design;

FIG. 2 is a right side elevational view thereof;

FIG. 3 is a left side elevational view thereof;

FIG. 4 is a top plan view thereof;

FIG. 5 is a bottom plan view thereof; and,

FIG. 6 is a rear elevational view thereof.

The broken lines are for illustrative purposes only and form no part of the claimed design.
